UNITED STATES PATENT OFFICE.

BENJAMIN SEDGELY SMITH, OF SYDNEY, NEW SOUTH WALES, AUSTRALIA.

HOLDER FOR BLOTTING-PAPER AND THE LIKE.

1,165,549.

Specification of Letters Patent. Patented Dec. 28, 1915.

Application filed January 12, 1914. Serial No. 811,640.

To all whom it may concern:

Be it known that I, BENJAMIN SEDGELEY SMITH, a citizen of the Commonwealth of Australia, and residing at No. 9 Jamieson street, in the city of Sydney, in the State of New South Wales, Commonwealth of Australia, have invented new and useful Improvements in Holders for Blotting-Paper and the like, of which the following is a specification.

10 specification.
The object of this invention is to facilitate the use of blotting paper or other absorbing material when employed in drying or removing a superfluity of ink or other
15 liquid from paper or the like.

10 A holder constructed according to this invention allows of a more even pressure to be applied to the blotting paper or other medium thereby giving a better contact between the opposing surfaces than that obtained in present holders, as very often patches of ink are left undried or unab-sorbed through an uneven pressure and uneven contact being made and further-more 20 this holder may be used in conjunction with a letter "copy-book" so as to absorb the ex-cessive moisture that is applied to a sheet which is adapted to receive the impression, and still further may be used to complete 25 the copying process thereby obviating the necessity of a screw-press or the like.

The essential feature of this invention consists in the holder having a carriage framing with lateral rollers thereon and adapted to be reciprocated so that the rollers thereof will bear upon the blotting paper or other medium during reciprocation of the said carriage framing.

The carriage framing has ear pieces or lugs taking around a pair of parallel longitudinal rods rigidly affixed to end vertical members, and to which members a strip or strips of blotting paper or the like are attached in any suitable manner.

45 But in order that this invention may be clearly understood reference will now be made to the drawings herewith in which—

Figure 1 is a perspective view of the holder constructed according to this invention. Fig. 2 a longitudinal central sectional elevation thereof. Fig. 3 a cross sectional elevation on line 3-3 of Fig. 2. Fig. 4 a fragmentary view of a sectional elevation on plane 4-4 of Fig. 1.

55 Referring to Figs. 1 to 4 the holder con-

sists of a pair of parallel longitudinal guide rods 10 rigidly affixed to the end vertical members 11 and 12 by screws 13 and which members have their lower longitudinal edges slightly and inwardly curved back. 60

Loosely attached to the vertical members 11 and 12 by means of screws 14 and coil springs 15 are the clamping members 16 and centrally of each clamping member is an orifice through which passes the clamping screw 17 provided with a milled head 18. 65

The ends of a strip or strips of blotting paper 19 or the like are fastened to the vertical members by the clamping plates 16 and clamping screws 17. A pair of laterally positioned rollers 20 are adapted to bear upon the blotting paper 19 or the like and have trunnions 21 taking into bearing orifices contained in the resilient depending members 22 of the carriage framing 23. The carriage framing is loosely secured to the longitudinal parallel guide rods 10 and retained in position by lugs or ear pieces 24 taking around the guide rods 10 and provided with sufficient clearance space 25 so that on reciprocating the carriage framing 23 no pressure will be brought to bear upon the rods 10 when pressure is applied to the knob or handle 26 that is rigidly affixed to the carriage framing 23. 70 75 80 85

Thus it will be clearly seen that when pressure is applied to the carriage framing 23 by virtue of the knob 26, said pressure is conveyed by the rollers 20 to the blotting paper 19 or other medium and by the reciprocation of the carriage framing 23 an even pressure is distributed over the blotting paper 19 or the like thereby insuring good contact being made between the two opposing surfaces and thereby readily drying and absorbing the ink or other aqueous matter and as in the case of using a letter copying book or the like, completing the copying process.

What I claim and desire to secure by Letters Patent of the United States is:—

1. A device of the kind described comprising in combination a framing, consisting of a pair of longitudinal parallel rods and end vertical members, a strip of absorbent material arranged between the end vertical members, clamping members for the absorbent material arranged upon the vertical members and having the lower edges turned inwardly, a carriage adapted to be reciprocated along said framing and a set 1

of laterally disposed rollers adapted to bear upon the absorbent material upon reciprocation of the carriage.

2. A device of the kind described comprising in combination a framing consisting of a pair of longitudinal parallel rods and end vertical members, a strip of absorbent material arranged between the end vertical members, clamping members for the absorbent material arranged upon the vertical members and having the lower edges turned inwardly, means for resiliently mounting the clamping members upon the vertical members of the framing, a carriage adapted to be reciprocated along said framing and a set of laterally disposed rollers adapted to bear upon the absorbent material upon reciprocation of the carriage.

3. A device of the kind described comprising in combination a framing consisting of a pair of longitudinal parallel rods and end vertical members, a strip of absorbent material arranged between the end vertical members, clamping members for the absorbent material arranged upon the vertical members and having the lower edges turned inwardly, means for resiliently mounting the clamping members upon the vertical members of the framing, means for varying the resiliency of the mounting, a carriage adapted to be reciprocated along said framing and a set of laterally disposed rollers adapted to bear upon the absorbent material upon reciprocation of the carriage.

35 4. A device of the kind described comprising in combination a framing consisting of a pair of longitudinal parallel rods and end vertical members, a strip of absorbent material arranged between the end vertical

members, a carriage adapted to be reciprocated along said framing, lugs adapted to fit partially around the longitudinal parallel rods with clearance space, a set of laterally disposed rollers adapted to bear upon the absorbent material upon reciprocation of the carriage, members depending from the reciprocating carriage for supporting the laterally disposed rollers, and means for loosely mounting the reciprocating carriage upon the framing.

5. A device of the kind described comprising in combination a framing consisting of a pair of longitudinal parallel rods, end vertical members upon said longitudinal parallel rods a strip of blotting paper arranged between said end members, clamping plates for the blotting paper, screws connecting the end members with the clamping plates, springs arranged between the end members and the clamping plates, a carriage adapted to be reciprocated along said framing, lugs adapted to fit partially around the longitudinal parallel rods with clearance spaces, a set of laterally disposed rollers adapted to bear upon the absorbent material upon reciprocation of the carriage, members depending from the reciprocating carriage for supporting the laterally disposed rollers, and means for loosely mounting the reciprocating carriage upon the framing.

In testimony whereof I have hereunto set my hand in the presence of two witnesses this seventeenth day of November one thousand nine hundred and thirteen.

BENJAMIN SEDGELY SMITH.
